UNITED STATES PATENT OFFICE

136,379

DESIGN FOR AN EYE SHIELD

Joseph E. Du Bois, Detroit, Mich., assignor, by direct and mesne assignments, of one-fifth to Virginia I. Du Bois, Detroit, Mich., one-fifth to Lauriene T. Holzworth, North Tonawanda, N. Y., and one-fifth to Rita C. Sterne, one-fifth to Eileen Silbert, and one-fifth to Florence E. Taylor, all of Buffalo, N. Y.

Application February 20, 1943, Serial No. 109,591

Term of patent 14 years

To all whom it may concern:

Be it known that I, Joseph E. Du Bois, a citizen of the United States, residing at Detroit, county of Wayne, in the State of Michigan, have invented a new, original, and ornamental Design for an Eye Shield, of which the following is a specification, reference being made to the accompanying drawing, forming part thereof.

Fig. 1 is a front view, in perspective, of an eye shield showing my new design.

Fig. 2 is a rear view thereof, in perspective.

Fig. 3 is an end view thereof, in perspective.

I claim:

The ornamental design for an eye shield, as shown.

JOSEPH E. DU BOIS.
